UNITED STATES PATENT OFFICE.

JOHN M. ADAMS AND WILLIAM F. CARTER, OF SAN FRANCISCO, CALIFORNIA.

ORE-CONCENTRATOR.

SPECIFICATION forming part of Letters Patent No. 337,471, dated March 9, 1886.

Application filed October 21, 1885. Serial No. 180,545. (No model.)

To all whom it may concern:

Be it known that we, JOHN M. ADAMS and WILLIAM F. CARTER, each of the city and county of San Francisco and State of California, have invented an Improvement in Ore-Concentrators; and we hereby declare that the following is a full, clear, and exact description of the same.

Our invention relates to that class of ore-concentrators in which is employed an endless traveling belt upon a frame or table to which a shaking or vibratory motion is imparted; and our invention consists in certain details of construction and combination of parts, as we shall hereinafter fully describe and claim.

The object of our invention is to provide a concentrator which, by reason of the variable and modified motions which are imparted to it, is adapted for more general use or application than the ordinary concentrators to which a single movement is given. Different kinds of ore and other material may, therefore, be treated on our concentrator and be subjected to the most advantageous motions for the end in view.

A further object is to provide a simple mechanism for the uphill travel of the belt.

Referring to the accompanying drawings, Figure 1 is a perspective view of one side of our concentrator. Fig. 2 is a plan of the concentrator. Fig. 3 is a vertical cross-section through the driving-drum, showing the back gearing.

35 A is the bed-frame of the machine, from which is supported upon yielding or spring standards *a* the inclined table B, which carries in its upper end the driving-drum C, by which the endless belt D is caused to travel. 40 The course of the endless belt is the same as in concentrators of this class—namely, around the upper drum down into a tank underneath, (not here shown,) and around a drum at the lower end of the frame.

45 E is the main driving or power shaft, mounted in suitable bearings on one side of and parallel with the bed-frame. This shaft carries the driving-pulley *e*, and has cranks *e'*, as shown. Mounted transversely on the bed-frame under the table B is a shaft, F, which has a fly-wheel, *f*, at one end, and is formed

with cranks *f'*. Upon the driving-shaft E is a beveled gear, G, which meshes with a beveled gear or pinion, G', on the shaft F. From the cranks *e'* of the driving-shaft E extend 55 the connecting bars or straps H transversely under the table, and are secured thereto at the points *e''*, Fig. 2.

From the cranks *f'* of the transverse shaft F extend bars or straps H', parallel with the table B and connected therewith at the points *f''*, Fig. 2. These bars or straps are connected with their cranks and with the table in the following manner: They are pivoted to two-part sleeved boxes I by means of vertically-arranged pins *i*, whereby they are adapted to have a slight movement in a horizontal plane to accommodate themselves to the movement of the table. The boxes I are fitted over the cranks of the shafts E and F. 60 The other ends of the bars or straps are connected at the points *e''* and *f''* by means of vertical pins, whereby they may accommodate themselves to the movement of the table in the same manner as at their first ends. 70

75 It will now be observed that the rotation of the shaft E communicates, through its cranks *e'* and the bars or straps H, a lateral vibration or side shake to the table, while through the beveled gears G and G', the cross-shaft F, its 80 cranks *f'*, and bars or straps H' the table has imparted to it a longitudinal vibration or end shake. The combination of these two movements, acting simultaneously, enables us, by variations in the crank-centers and in the 85 relative size of the gears G G', to produce variable and modified motions, as we shall now explain.

In Fig. 1 it will be seen that the gear or pinion G' is one-half as large and has one-half 90 as many teeth as the gear G, so that a complete rotation of the latter gear gives two rotations to the former one. It will also be seen that the cranks of the shafts E and F are what is known as "quartering"—that is to say, 95 their starting-centers are removed by ninety degrees. In this figure the cranks *e'* are shown at their outward limit or stroke, while the cranks *f'* are at their top centers. This quartering of centers of the cranks, together with 100 the proportional or relative sizes of the gears G G', results in imparting to the table a motion

which may be correctly described as that of a figure 8—that is to say, each point in the table, and consequently each point in the traveling belt carried by the table, describes a figure 8. Now, by leaving the cranks quartering, as described, and changing the gear G' for a gear which has the same number of teeth as the gear G, we cause each point of the table to move through a perfect circle; then, by leaving the gears of the same size and making the cranks of the two shafts on the same center, we obtain a diagonal motion in a straight line at an angle of forty-five degrees. Between these limits, by changing the relative centers of the cranks, we may obtain modifications or variations between the complete circle and the line at an angle of forty-five degrees, and by changing the relative sizes of the gears G G' we may modify and vary the compound movement between the figure 8 and that of the circle.

As the drum C is carried by the shaking table, it is evident that driving mechanism must be employed, which will not interfere with or be affected by the various motions of the table. The mechanism for this purpose is as follows: Referring to Fig. 3, it will be seen that the shaft J passes loosely through the hubs or gudgeons c of the driving-drum C. On one end of the shaft J is a pulley, K, which is attached to the shaft by means of a movable key, k, so that the pulley can run loose, when desired, or be fastened to the shaft. Upon the driving-shaft E, Figs. 1 and 2, is feathered a cone-pulley, L. Pivoted to the bed-frame A is an arm, M, which carries in one end a shaft, m, upon which run loosely two small pulleys, N and N', the outer and inner one, respectively. Secured to the bed-frame is an arm, O, in one end of which is a pulley o, and a pulley, o', in the other end. A belt, P, passes over the cone-pulley under the two loosely - running and suspended pulleys N N', under the two pulleys o o', and over the driving-pulley K. The pivoted connection of the pulleys N N' causes them to act as tighteners for the belt, and there being only a belt or flexible connection between the driving - shaft and the pulley K of the drum, said drum may follow the various movements of the table on which it is mounted without interference from the driving mechanism. In order to vary the speed of the driving mechanism, we have a screw - spindle, Q, one end of which is connected by an arm, q, with the hub of the cone-pulley L. By operating this screw the cone-pulley may be pushed along the shaft E away from the upper end of the machine, thus presenting a larger diameter to the belt L, and thereby causing a more rapid travel, or said pulley may be moved in the opposite direction with the opposite effect. The swinging pulleys N N' permit this movement of the cone-pulley, while still keeping the belt tight, and they adjust themselves by moving in or out on their shaft. This direct power, which is applied to the drum, would result in too great

speed for the purposes of concentration, and in order to reduce this speed we back-gear the drum, as shown in Fig. 3.

On the end of the shaft J is a small pinion, r, which meshes with a large gear, R, said gear carrying a small pinion, r', which meshes back with the large gear R' on the hub or gudgeons c of the drum C.

It is not essential that the shaft J should pass through the drum, as it may cross in other positions.

Having thus described our invention, what we claim as new, and desire to secure by Letters Patent, is—

1. In an ore-concentrator, the combination of the table B and the endless traveling belt D thereon, with mechanism comprising power-transmitting devices, and longitudinal and transverse bars or straps for imparting to said belt and table a vibrating motion, the result of lineal motions at right angles acting simultaneously the one transversely of the table and the other parallel with its length, substantially as herein described.

2. In an ore-concentrator, the table B and the endless traveling belt D thereon, in combination with the power-shaft E, parallel with the table, and the shaft F, transverse of the table, miter-gears between said shafts, cranks on the shafts, and transverse and longitudinal bars or straps connecting the cranks with the table, whereby a motion is imparted to said table, the result of initial movements at right angles, substantially as herein described.

3. In an ore-concentrator, the table B and endless traveling belt D thereon, in combination with power-shaft E, parallel with the length of the table, a shaft, F, transverse of said table, the cranks e f' on said shafts quartering with each other, and the bars or straps H H', connecting said cranks with the table, the gears G on the shaft E, and the gear G' on shaft F, said gears bearing the proportions to each other of two to one, substantially as herein described.

4. In an ore-concentrator, the table B and endless traveling belt D thereon, in combination with shaft E and transverse shaft F, miter-gears between said shafts, cranks quartering with each other on said shafts, and the bars or straps H H', connecting the cranks with the table, substantially as herein described.

5. In an ore-concentrator, the shaking table B, having drum C, and the endless traveling belt D on said table and drum, in combination with the mechanism for causing the belt to travel, consisting of a shaft connected with the drum, a pulley, K, on the shaft, and pulley L on the driving-shaft, swinging tightener-pulleys under the pulley L, and guide-pulleys under pulley K, and an endless belt, P, substantially as herein described.

6. In an ore-concentrator, the shaking table B, having drum C, and the endless belt D on said table and drum, in combination with the shaft J, geared to the drum, the pulley K

on the shaft, the driving-shaft E, the cone-pulley L on said shaft, the swinging tightener-pulleys N N', and the guide-pulleys o o' and the endless belt P, all arranged and adapted 5 to operate substantially as herein described.

7. In an ore-concentrator, the shaking table B, having drum C and the endless belt D, in combination with the shaft J, having pulleys K, back-gearing between said shaft and 10 the drum, the driving-shaft E, the cone-pulley L on said shaft, the swinging tightener-pulleys N N', and the guide-pulleys o o', and the belt P, substantially as herein described.

8. In an ore-concentrator, the shaking frame 15 B, having drum C, and endless belt D thereon, in combination with the shaft J, connected

with the drum, the pulley K on the shaft J, the shaft E, and adjustable cone-pulley L, feathered on shaft E, the adjustable tightener-pulleys N N', the guide-pulleys o o', the endless 20 belt P, by which the drum is driven, and the means for regulating the speed, consisting of the screw-spindle Q, connected with the cone-pulley L, substantially as described.

In witness whereof we have hereunto set 25 our hands.

JOHN M. ADAMS.
